TANK HEATER

Julius H. Luedke, Hartley, Iowa

Application February 14, 1931. Serial No. 515,839

2 Claims. (Cl. 126—360)

This invention relates to tank heaters, and has for one of its objects to provide a novel heater of this character which shall be adapted to permit the use of kerosene or other distillate as a fuel.

To attain the foregoing and other objects, the nature of which will appear as the description proceeds, the invention comprehends the provision of a heater which shall embody a body adapted to be immersed in the water of a tank, a flue 5 extending from the body to a point above the surface of the water, a fuel vaporizing and combustion chamber communicating with the body and also adapted to be immersed in the water, and a tube adapted to extend from a point above the 10 surface of the water to the vaporizing and combustion chamber and adapted to deliver fuel and air to said chamber.

The invention further comprehends the provision of a heater of the character stated wherein the rear end of the chamber shall, during the initial operation of the heater, become heated sufficiently to vaporize and ignite the fuel as it is delivered thereto, and wherein the tube shall deliver the fuel and air to such end of the chamber in a manner to effect the thorough vaporization of the fuel and the thorough commingling of the vapor and air.

The invention further comprehends the provision of a heater of the character stated wherein the tube shall be adapted to deliver the fuel to the bottom of the chamber at a point in advance of the rear end of the chamber, and wherein the tube shall be adapted to deliver the air to the chamber in such manner as to force the fuel rearwardly against said end of the chamber so as to effect the vaporization of the fuel and the commingling of the vapor and air.

The invention is hereinafter more fully described and claimed, and illustrated in the accompanying drawings, wherein:—

Figure 1 is a view in side elevation of a tank heater constructed in accordance with my invention.

Figure 2 is a top plan view of the tank heater.

Figure 3 is a sectional view taken on the plane indicated by the line 3—3 of Figure 2.

Figure 4 is a sectional view taken on the plane indicated by the line 4—4 of Figure 1.

Figure 5 is a sectional view taken on the vertical plane indicated by the line 5—5 of Figure 3, and

Figure 6 is a perspective view of the fuel guiding means for the fuel and air delivery tube.

Referring in detail to the drawings, 1 designates the body, 2 the flue, 3 the vaporizing and com-

bustion chamber, and 4 the fuel and air delivery tube of the tank heater. The body 1 is of cylindrical formation and disposed vertically, and the flue 2 extends upwardly from the upper end of the body. The vaporizing and combustion chamber 3 which is also of cylindrical formation and which is smaller diametrically than the body 1, is horizontally disposed, and has its rear end fully closed and its front end fully opened and in communication with the lower end of the body 1. 60 The delivery tube 4 which is smaller diametrically than the vaporizing and combustion chamber 3, occupies a downwardly and forwardly inclined position, and has its lower end arranged within the rear end portion of the chamber. 65

The upper end of the delivery tube 4 which is located in a plane above that in which the upper end of the body 1 is located, is entirely open and the lower end of the delivery tube is arranged with its axis at an angle of about 45° to the axis 70 of the vaporizing and combustion chamber 3. The lower portion of the lower end of the delivery tube 4 is open to provide a discharge port 5, and the closed upper portion 6 of this end of the tube constitutes a baffle plate. The discharge port 5 75 of the delivery tube 4 is located slightly above the bottom of the vaporizing and combustion chamber 3 and slightly in advance of the rear end 7 of the chamber. The bottom wall of the vaporizing and combustion chamber 3 is provided with ribs 8 80 which are located forwardly and rearwardly of the discharge port 5 of the delivery tube 4 and the space between the ribs 8 constitutes a fuel well into which the lower end of the delivery tube 4 extends. 85

A boss 9 is secured to the delivery tube 4 near the upper end of the latter and it extends laterally from the tube and communicates at its inner end with a fuel intake port 10 formed in the tube. A needle valve 11 having a handle 12 is secured to the boss 9, and provides means by which the amount of fuel entering the intake port 10 may be regulated and controlled. A split ring 13 having its end 14 thereof secured to the delivery tube 4, extends upwardly and forwardly from the upper end of the tube, and constitutes a support for a fuel tank 15. A pipe 16 extends from the bottom of the fuel tank 15 to the valve 11, the tank being located above the needle valve so as to cause the fuel to flow by gravity from the former to the latter. The other end 17 of the ring 13 is secured to the end 14 of the ring by a bolt 18 which, in addition to firmly clamping the ring about the fuel tank 15, serves as a support 100 for a guard 19 for the upper end of the delivery 105 tube 4. 110

tube 4. The guard 19 is spaced from the upper end of the delivery tube 4 to provide an annular air inlet port 20 for the tube.

5 A fuel conducting rod 21 located within the delivery tube 4, rests against the rear side of the tube, and extends from the upper end of the tube to the discharge port 5 of the tube. The lower end of the conducting rod 21 is forked, and the members 22 of such end are curved upwardly and forwardly and extend across the discharge port 5 of the delivery tube 4. The conducting rod 21 has a hooked upper end 23 which engages the upper edge of the delivery tube 4 and removably supports the rod within the tube.

10 In practice, the heater is placed in a water tank with the body 1, the vaporizing and combustion chamber 3, and the lower end portion of the delivery tube 4 immersed in the water, and with the flue 2, the upper end of the delivery tube, and the fuel tank 15 located above the surface of the water. The rear end of the vaporizing and combustion chamber 3 is supported by a bracket 24 which is secured to the lower side of the chamber. The vaporizing and combustion chamber 3 is welded to the body 1, the rear end 7 of the chamber is welded in place, the delivery tube 4 is welded to the chamber, and the ring 13 is welded to the delivery tube. The valve 11 is also located above the surface of the water, and it is opened until a starting supply of fuel is delivered to the fuel well of the vaporizing and combustion chamber 3. This supply of fuel is ignited to heat the rear end of the chamber 3 to a fuel vaporizing degree, and then the valve 11 is again opened. The fuel admitted to the delivery tube 4 flows through the discharge port 5 of the tube in to the bottom of the vaporizing and combustion chamber 3 where it is vaporized.

15 The air entering the delivery tube 4 is directed by the baffle 6 of the tube against the bottom wall of the vaporizing and combustion chamber 3 in a direction to cause it to move initially in the direction of the rear end 7 of the chamber and carry the fuel against such end. This end of the vaporizing and combustion chamber 3 is heated to the highest degree, and in view thereof and as the fuel is forced by the incoming air against such end, the fuel will be thoroughly vaporized and the air and vapor will be thoroughly commingled. 20 I have found by actual tests that the draft is as indicated by the arrows in Figure 3. It will be seen that the baffle 6 extends downward to a point intersecting the center line of draft or the axial center of the combustion chamber 3 and that the lower end of the bottom of pipe 4 is immersed in the fuel collected between the ribs 8. With this construction a large part of the flames are discharged upward and rearward at the rear of the delivery tube and then move forward around the delivery tube heating its lower end. The burning commingled air and vapor flow forwardly between the rear end of the delivery tube 4 and the sides of the vaporizing and combustion chamber 3 into the body 1 and from the body through the flue 2. The fuel conducting rod 21 is only employed when it is necessary to create a very high temperature in order to prevent the freezing of the water in the tank. The fuel conducting rod 21 is particularly adapted and used for the purpose of lighting or starting the fire after which it may be pulled up to any extent desired or en-

tirely removed. It is not designed to be kept permanently in place in the position shown in Figure 3. When this is necessary the valve 11 is fully opened, and the fuel entering the delivery tube 4 is conducted by the rod 21 to the discharge port 5 of the tube, the fork 10 of the tube separating the fuel into two streams in order to enable it to be readily directed by the incoming air against the end plate 7 of the vaporizing and combustion chamber 3. When the rod 21 becomes heated it assists in vaporizing the fuel and also insures the free passage of the fuel in two streams through the delivery tube 4.

25 From the foregoing description, taken in connection with the accompanying drawings, it should be apparent that the heater is simple, durable and highly efficient, that it may be manufactured and sold at a comparatively low cost, and that it may be used for other purposes than heating water in tanks.

30 While I have described the principle of the invention, together with the structure which I now consider the preferred embodiment thereof, it is to be understood that the structure shown is merely illustrative and that such changes may be made, when desired, as fall within the scope of the invention as claimed.

35 What is claimed is:—

1. A tank heater comprising a body provided with a stack, a substantially horizontal vaporizing and combustion chamber opening at its forward end into said body and having its rear end closed, a downwardly and forwardly inclined fuel and air delivery tube of smaller cross section than the cross section of the combustion chamber, said tube 40 extending at its lower end into the combustion chamber and having the lower extremity of its lower wall spaced from the bottom of the chamber and delivering fuel on to said bottom forward of the rear closed end of the chamber, the lower edge of the tube extending downward and rearward, a baffle extending across the upper portion of the lower end of the tube and directing the air discharged from the lower end of the tube downwardly and slightly rearwardly toward the bottom of the combustion chamber, the chamber having two upwardly projecting ribs on its bottom between which the extremity of the lower end of the tube discharges, the ribs extending above the lower extremity of the lowest portion of the tube. 45

50 2. A tank heater comprising a body provided with a flue, a vaporizing and combustion chamber communicating at its forward end with the body and having its rear end closed by a vertical end plate, a downwardly and forwardly inclined fuel and air delivery tube having its lower end extending into the chamber to deliver fuel to the bottom of the chamber in advance of the end plate, a baffle disposed across the upper portion of the opening at the lower end of said tube, the lower edge of the tube extending downward and slightly rearward and the baffle extending downwardly and slightly rearward, a rod detachably engaged with the rear side of the tube and extending longitudinally thereof and provided at its lower end with upwardly directed members disposed below the baffles, and means for delivering liquid fuel to the tube, the tube being open at its upper end for the inlet of air.
